ACTION SLIDE FOR FIREARMS

Carl G. Swebilius, Hamden, Conn.

Application May 9, 1947, Serial No. 746,971

7 Claims. (Cl. 29—148)

1

The present invention relates in general to firearms and more especially to action-slide mechanism for automatic or semiautomatic firearms.

An object of the invention is to provide an improved method of making the action-slide mechanism of firearms.

A further object of the invention is to form action-slide mechanism for firearms by an improved method which requires relatively few operations, each of which is characterized by its simplicity and economy of performance.

A still further object of the invention is to form action-slide mechanism for firearms by an improved method wherein preliminary operations are performed simultaneously on a piece of stock from which a plurality of crosshead blanks are subsequently made.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a perspective view of a length of cylindrical bar stock from which a plurality of crosshead blanks are to be made, the cylindrical bar stock having two spaced parallel longitudinal apertures formed therethrough in accordance with the first step of the improved method of this invention;

Fig. 2 is an exploded perspective view of one of the crosshead blanks cut from the bar stock of Fig. 1; and of a pair of action-rods, the forward ends of which are adapted to fit in the longitudinal apertures of the cylindrical crosshead blank;

Fig. 3 is a view similar to Fig. 2 but with the action-rods inserted into the longitudinal apertures of the cylindrical crosshead blank;

Fig. 4 is an end elevation partly in section on line 4—4 of Fig. 3, the broken line indicating removal of stock from the periphery of the cylindrical crosshead blank and from the forward ends of the action-rods by the next succeeding step;

Fig. 5 is a perspective view of the cylindrical crosshead blank and action-rods following removal of stock from the peripheries thereof;

Fig. 6 is an end elevation partly in section on line 6—6 of Fig. 5 indicating by broken lines the next succeeding operations to be performed thereon;

Fig. 7 is a perspective view of the finished crosshead and the action-slide rods of Fig. 5 following the shaping of the recesses in the top and bottom of the crosshead blank and after

removal of the cylindrical stock left in the longitudinal apertures of the crosshead blank;

Fig. 8 is a broken plan view of the completed action-slide;

Fig. 9 is an end elevation partly in section on line 9—9 of Fig. 7.

For the purpose of illustrating the invention, an action-slide is shown of the type used in a semiautomatic rifle, but it will be understood that the invention may have other applications and is not limited to the firearm illustrated but includes all firearm structures within the scope of the appended claims.

The action-slide shown herein is characterized by a crosshead and a pair of action-rods, the latter being adapted to transmit the reciprocal movement of a fore-end to a breechblock for moving the latter to and from breech-closing position in the receiver of a firearm, as is well understood by those versed in the art. It will be appreciated, however, that but a single action-rod may be used where a relatively-small caliber gun warrants the lighter construction.

In carrying out the invention, a piece of cylindrical solid bar-stock 15 is selected of any suitable material such as steel and of a length such that it may be subsequently divided by transverse cuts, as indicated by the broken lines 16 in Fig. 1, into a plurality of cylindrical blanks 18 of substantially equal length from each of which a finished crosshead will be formed. The piece of cylindrical bar-stock 15 is adapted to be rigidly supported while a pair of apertures 17 are formed therethrough. These apertures 17 may be formed either by a boring or drilling process and the longitudinal axes of the apertures 17 are formed parallel to the longitudinal axis of the cylindrical bar-stock and in a common diametric plane, the longitudinal axis of each aperture being adjacent

40 the opposite extremities respectively of the diametric plane but spaced inwardly transversely from the periphery of the cylindrical bar by a distance equal substantially to the radius of its respective aperture 17 plus one thirty-second of an inch. The latter dimension is not critical but has been chosen as most satisfactory from the standpoint of uniformity and economy of operation in the improved method of this invention.

45 After the longitudinal apertures 17 have been formed in the cylindrical bar-stock 15, the latter is divided by transverse cuts, as indicated at 16, into a plurality of crosshead blanks 18, as shown in Fig. 2, each of which has two longitudinal apertures 19 extending therethrough and 50 constituting short lengths of the longitudinal aperture 17 of the original cylindrical bar-stock 15. Each longitudinal aperture 19 is then fitted with an action-rod 20 which comprises a solid cylindrical rod of predetermined length, the forward end 21 of which is adapted to make a close

fit in its respective aperture 19 and to terminate substantially flush with the front face 22 of the cylindrical crosshead blank 18. The forward ends 21 of the action-rods are then secured in the respective apertures 19 by a solder such, for example, as silver solder or an equivalent fastening-means. The completely assembled crosshead blank and action-rods are shown in Fig. 3.

This assembly is now adapted to be mounted in a lathe or similar turning tool whereupon the periphery of the crosshead blank 18 is turned down substantially uniformly to a predetermined diameter which corresponds substantially to the transverse dimension of the finished crosshead. The amount of stock removed by this trimming operation is shown generally by the broken lines in Fig. 4 and will be seen to include a substantial portion of the outer peripheries of the forward ends 21 of the action-rods as a consequence of which the latter intersect the periphery of the turned-down cylindrical crosshead blank 23, as indicated by the longitudinal spaced parallel lines 24 in Fig. 5. Since the turning operation is performed throughout the length of the cylindrical crosshead blank 23, a substantially-square shoulder 25 is formed adjacent the forward end of each action-rod in a plane coincident with the rear face 26 of the crosshead blank 23, each shoulder 25 projecting transversely from the periphery thereof, as indicated clearly in Fig. 8.

A crosshead for a firearm of the class described is adapted customarily to reciprocate longitudinally beneath the barrel of the firearm and in juxtaposition thereto, and hence the top side of the crosshead is formed with a substantially-semicylindrical recess so as to provide clearance for the underside of the barrel and permit the longitudinal axis of the action-slide to be located as near as possible to the longitudinal axis of the barrel.

Hence, the next step in forming the action-slide of this invention is that of supporting the crosshead blank 23 and action-rods 20 and milling or otherwise forming a semicylindrical recess 27 in the topside of the cylindrical crosshead blank 23, as indicated in Figs. 6, 7 and 9, the depth and configuration of the recess 27 being shown by the broken lines in Fig. 6. In the embodiment shown, the semicylindrical recess 27 formed in the topside of the crosshead blank intersects a portion of the periphery of the forward end 21 of each action-bar, as indicated by the longitudinal spaced parallel lines 28 in Figs. 7 and 8. Moreover, the milling operation is adapted to be carried rearwardly from the crosshead blank to the rear extremities of the action-rods 20, as a consequence of which the upper longitudinal edges 29 thereof are formed with beveled surfaces constituting substantially cylindrical surfaces of revolution which provide clearance for the underside of the barrel.

In a preferred embodiment, the recessed crosshead blank indicated at 30 in Figs. 7, 8 and 9 may be lightened by providing it with a cutout on its underside, the cutout being substantially rectangular in cross section, as indicated at 31, and formed by a milling or similar shaping operation.

The next step in the action-slide forming operation is that of providing longitudinal flats 32 on the inside walls of the action-rods, as indicated by the broken lines in Fig. 6. These longitudinal flats may be made by a milling tool in a single operation or in two operations, the milling cut extending from the rear face 33 of the crosshead 30 to a point forwardly of the rear-end extremities

5 34 of the action-rods. In accordance with this construction, the rear ends of the action-rods are formed with integral inwardly-projecting lugs 35, each of which is adapted to be provided with a transverse aperture 36, the apertures 36 being in axial alignment and adapted to receive a transverse pivot-pin for pivotally connecting the rear ends of the action-rods to the breechblock, in a manner well known to the art.

10 Although the proposed method of forming the action-rod apertures in the crosshead blanks is by drilling longitudinal apertures through a cylindrical bar and subsequently cutting the latter into a plurality of crosshead blanks having action-rod apertures extending therethrough, it will be understood that it is within the purview of the invention to form each crosshead blank separately and to drill a pair of action-rod apertures all the way through each blank, or only part 15 way through each blank; and that either one or two apertures (and their respective action-rods) may be utilized, depending upon the strength requirements of the firearm. Further, the crosshead, together with the action-rods, may be formed with flat exterior sides to reduce the 20 weight of the firearm and provide a more streamlined appearance.

25 Although the above-described sequence of operations has been followed successfully in the manufacture of action-slides in accordance with the improved method of this invention, it will be understood that such steps as those of forming the flats 32 on the inside walls of the action-rods and milling the semicylindrical recess 27 in the crosshead blank 23 may be performed in the reverse order, the criterions being those of convenience and economy in manufacture.

30 The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended 35 to be embraced therein.

40 I claim:

45 1. In the manufacture of firearms, the method of forming an action-slide mechanism embodying a crosshead and action-slide rod which method comprises the steps of; boring a longitudinal aperture into a substantially-cylindrical blank parallel to and spaced laterally from the longitudinal axis thereof, securing one end of an action-rod in said longitudinal aperture, thereafter shaping said cylindrical blank and the corresponding end of said action-rod to the form of a crosshead by removing stock from the periphery of said blank and from the periphery of the corresponding end of said action-rod in a single operation, and then milling a flat on the 50 inside wall of said action-rod.

55 2. In the manufacture of firearms, the method of forming an action-slide mechanism embodying a crosshead and action-slide rod which method comprises the steps of; boring a longitudinal aperture into a substantially-cylindrical blank parallel to and spaced laterally from the longitudinal axis thereof, securing one end of an action-rod in said longitudinal aperture, thereafter reducing the over-all diameter of said cylindrical blank to the over-all diameter of a crosshead by removing stock from the periphery of the cylindrical blank and from the corresponding 60 end of said rod in a single operation and

thereafter milling a concave barrel-clearance recess in the top side of said cylindrical blank and the upper edge of said rod.

3. In the manufacture of firearms, the method of forming an action-slide mechanism embodying a crosshead and a pair of action-slide bars which method comprises the steps of; boring a pair of longitudinal apertures through a substantially-cylindrical bar, each aperture being parallel to and spaced laterally from the longitudinal axis thereof, dividing said cylindrical bar into a plurality of longitudinally-apertured cylindrical blanks from which to form a corresponding number of crossheads, securing one end of an action-rod in each longitudinal aperture of one of said cylindrical blanks, thereafter reducing the over-all diameter of said cylindrical blank to the over-all diameter of a crosshead by removing stock from the periphery of the cylindrical blank and from the corresponding ends of said action-rods in a single operation, thereafter milling a concave barrel-clearance recess in the top side of said cylindrical blank and the upper edges of said action-rods and then milling a substantially-rectangular lightening-recess in the bottom side of said cylindrical blank.

4. In the manufacture of firearms, the method of forming an action-slide mechanism embodying a crosshead and action-slide rod which method comprises the steps of; drilling a longitudinal aperture through a substantially-cylindrical blank parallel to and spaced laterally from the longitudinal axis thereof, securing one end of an action-rod in said longitudinal aperture, thereafter shaping said cylindrical blank and the corresponding end of said action-rod to the form of a crosshead by turning off stock from the periphery of said blank and from the periphery of the corresponding end of said action-rod in a single operation, forming an external shoulder on said action-rod at its intersection with the rear end of said cylindrical blank by removing stock from the periphery of said cylindrical blank and from the corresponding end of said rod in a single operation and then forming an inwardly-projecting lug-on the inside of said action-rod by milling a flat on the inside wall thereof.

5. In the manufacture of firearms, the method of forming an action-slide mechanism embodying a crosshead and a pair of action-slide rods which method comprises the steps of; drilling a pair of longitudinal apertures through a substantially-cylindrical bar, each aperture being parallel to and spaced laterally from the longitudinal axis thereof, dividing said cylindrical bar into a plurality of longitudinally-apertured cylindrical blanks, securing one end of an action-rod in each longitudinal aperture of one of said cylindrical blanks, thereafter shaping each cylindrical blank to the form of a crosshead by removing stock from the periphery thereof and from the periphery of the corresponding end of each action-

rod, and then milling a flat on the inside wall of each of said action-rods.

6. In the manufacture of firearms, the method of forming an action-slide mechanism embodying a crosshead and a pair of action-slide rods which method comprises the steps of; drilling a pair of longitudinal apertures through a substantially-cylindrical bar, each aperture being parallel to and spaced laterally from the longitudinal axis thereof, dividing said cylindrical bar into a plurality of longitudinally-apertured cylindrical blanks from which to form a corresponding number of crossheads, securing one end of an action-rod in each longitudinal aperture of one of said cylindrical blanks, thereafter shaping each cylindrical blank and the corresponding ends of said pair of action-rods to the form of a crosshead by removing stock from the peripheries thereof and from the periphery of the corresponding ends of said pair of action-rods in a single operation, forming external shoulders on said action-rods at their points of intersection with the rear end of said cylindrical blank by removing stock from the periphery of said cylindrical blank and from the corresponding ends of said action-rods in a single operation and then forming inwardly-projecting lugs on the inner walls of said action-rods by milling flats on the respective inner walls thereof.

7. In the manufacture of firearms, the method of forming an action-slide mechanism embodying a crosshead and a pair of action-slide rods which method comprises the steps of; drilling a pair of longitudinal apertures through a substantially-cylindrical bar, each aperture being parallel to and spaced laterally from the longitudinal axis thereof, dividing said cylindrical bar into a plurality of longitudinally-apertured cylindrical blanks, securing one end of an action-rod in each longitudinal aperture of one of said cylindrical blanks, thereafter shaping each cylindrical blank to the form of a crosshead by removing stock from the periphery thereof and from the periphery of the corresponding end of each action-rod, and then milling a clearance-recess in the upper surface of said cylindrical blank and a longitudinal flat on the inside wall of each of said action-rods.
